His Attorney.

UNITED STATES PATENT OFFICE.

WILFRED ROTHERY WOOD, OF LONDON, ENGLAND.

FIRING WITH POWDERED FUEL.

Application filed May 11, 1923. Serial No. 638,357.

To all whom it may concern:

Be it known that I, WILFRED ROTHERY Wood, a citizen of the United States of America, residing in London, England, have invented certain new and useful Improvements Relating to Firing with Powdered Fuel, of which the following is a specification.

This invention relates to improvements in burning powdered fuel in a heating furnace such as a boiler furnace and has for its object to dry the fuel on its way to the pulverizer by means of the waste gases of the furnace.

In order that the temperature of the furnace gases may be sufficiently under control provision is made for mixing air with the furnace gases before they are passed over the fuel. For it will be obvious that if the temperature of the coal were raised to that at which incipient carbonization occurs, combustible matter would be lost unless the furnace gases were returned through the furnace after they had traversed the coal, which would defeat one of the objects of the invention, namely keeping out of the furnace the water in the fuel. Another object of mixing air with the furnace gases is to dilute them in respect of their content of water vapour, or, in more exact language, to diminish the partial pressure of the water vapour which they carry as a product of combustion of the fuel. The lower such partial pressure, the greater the drying capacity of the gases.

Another object of the invention is to avoid the nuisance created by delivering dust laden gases into the atmosphere at a low level. In passing through the coal to be dried the gases take up from the coal a portion of dust which, although quite small when considered as lost fuel is sufficiently important when considered as dust in discharged gases. The invention avoids this objection by returning the gases which have passed through the fuel, to the flue of the furnace. By this expedient the dust is in part deposited after the manner of flue dust generally and in part dissipated at a high level with the main volume of flue gases.

To ensure satisfactory working it is generally best to withdraw the hot gases from the flue by means of a fan or the like.

In the accompanying drawings Fig. 1 is a diagram representing a boiler furnace in-

stallation to which the invention is applied, and Fig. 2 illustrates a modification.

Referring to Fig. 1 of the drawings, *a* indicates a vertically disposed drying chamber, provided with a centrally disposed chute *b* extending longitudinally thereof, through which chute the fuel is fed to the hopper *k* of a pulverizer *l*. The portion of the chute *b* within the chamber *a* is provided with multiple openings, preferably defined by a series of slats or bars in louver formation, to admit free circulation of gaseous drying media to and through the chute. Leading into the upper part of the chamber *a* is a pipe *e* which is connected to the chimney or flue *d* of the furnace or other heating unit in which the fuel is to be burned and near the bottom of the chamber *a*, there is connecting a pipe *i* which leads back into the chimney or flue *d*, the latter pipe being provided with a suction fan *g* and a regulating damper *h*. The pipe *e* is provided with a gate or damper *f* cooperating with an air inlet in the wall of the pipe, by means of which an accurately regulated supply of air may be admitted to the pipe and admixed with the flue gases or products of combustion before the latter enter the drying chamber. In order to cause the mixture of flue gases and tempering air to pass at least twice through the body of fuel being fed through the chute *b*, a baffle *c* is disposed between the chute and wall of the chamber *a* and between the discharge end of pipe *e* and the intake end of pipe *i*, so that the gases will pass transversely through the slotted openings in the upper part of the chute and in a reverse direction in the lower part of the chute, as indicated by the arrows.

The operation of the apparatus is as follows: The coal is fed into the top of the drying chamber through the chute *b* and the products of combustion or furnace gases are taken from the flue or chimney *d* through the pipe *e*, delivered into the upper part of the chamber *a*, and passed transversely through the openings in the chute *b* and the fuel in the latter, thence downward in the chamber *a* and back through the slotted lower end of the chute and the fuel therein to the exhaust pipe *i* back to the chimney. The furnace gases would, under ordinary conditions, be of too high a temperature to admit to the drying chamber, and would

be liable to cause incipient combustion of the fuel and would possibly produce an explosion if any material amount of the fuel were in a highly pulverized or com-
5 minuted condition, and in order to prevent these contingencies the temperature of the furnace gases is lowered to the necessary extent by admitting air through the opening controlled by the valve or damper *f*,
10 the latter being adjusted to admit just sufficient air to effect the desired result, namely, to reduce the temperature of the furnace gases entering the drying chamber below the combustion point of the fuel. The fan
15 *g* and the damper *h* may be regulated to accurately fix the rate of flow of the drying medium to and through the drying chamber and the fuel therein and also to deliver the furnace gases and any fine particles of fuel
20 which may be taken up thereby into the chimney or stack *d*. The particular advantages of this coordination of apparatus, are that the fuel will be effectively dried before reaching the pulverizer and the moisture
25 and the drying medium separated from the fuel and diverted into the chimney or stack, so that neither the moisture content of the fuel nor the furnace gases are delivered, in any appreciable quantities to the furnace,
30 but, on the contrary, the completely dried and pulverized fuel is delivered to the furnace in the best possible condition to effect complete combustion. It will be understood that any appropriate means for
35 feeding the comminuted fuel from the pulverizer to the furnace may be employed and that illustrated in Fig. 1 is merely exemplary, the same comprising a screw conveyer *m* for delivering the pulverized fuel
40 from the pulverizer *l* to a feed chute *n*, which latter is provided with a brush or

similar propelling device *p* near its lower end which is effective in projecting the powdered fuel through the fuel opening *o* in the furnace wall.

The construction shown in Fig. 2 is similar in all respects to that illustrated in Fig. 1, except that the suction fan *g'* and the damper *h'* are located in the pipe *e* supplying the furnace gases to the drying chamber, this arrangement being preferred where it is found desirable to control the gases entering the drying chamber. In each case, however, the damper or valve *f* is adjusted to admit the desired proportion of air to the furnace gases, as hereinbefore explained, and the damper *h* or *h'* is operated to control the total volume of gases passing through the drier. These adjustments necessarily are made with reference to the proportion of moisture in the fuel and also the nature of the latter in respect to the temperature at which it loses its hydro-carbon vapors, as will be understood.

What I claim is:

The method of preparing and burning fuel, which comprises feeding the fuel to a drier, passing the products of combustion from the furnace in which burning is effected through said drier, admixing air with the products of combustion in quantities sufficient to reduce the temperature of the latter below the combustion point of the fuel prior to the admission of said products to the drier, separating the drying medium from the fuel, pulverizing the fuel, and feeding the dried and pulverized fuel to the furnace.

In testimony whereof, I have signed my name to this specification.

WILFRED ROTHERY WOOD.
